6 Claims. (Cl. 137—624.19)

This invention relates to improvements in controllers and refers more particularly to controllers in which time provides the basic control and which are particularly adaptable for use in controlling flow of well fluids in various manners.

The controller of this invention can be used in a variety of industrial applications where a number of pneumatically powered two-way or three-way motor valves are required to be operated by remote control at selected times in relation to a common time base and for selected durations of time.

Another object is to provide a controller utilizing a pilot valve for alternately supplying gas under pressure to a control device and exhausting it from such device to the atmosphere in which a resilient means is employed to hold the pilot valve in one position and a means is provided for over-riding the resilient means at timed intervals to allow pilot valve to assume the other position and thus provide a timed control.

Another object is to provide a controller of the type set out in the preceding paragraph wherein the means for over-riding the resilient means includes a link attached to a weight which is slowly lifted, or a spring which is slowly compressed, over an appreciable time interval by a clock in such a way that although the power of the clock is insufficient to supply directly and instantaneously enough force to overcome the primary force keeping the pilot valve in said one position, it can, over a much longer space of time due to a mechanical advantage or cam-like linkage, raise the weight or compress the spring which when released provides a force sufficient to over-ride the resilient force instantaneously with a snap action.

Another object is to provide in a controller of the type mentioned in the last paragraph, for a ratchet which rises slowly and engages with the resilient means to over-ride it as aforesaid and which is itself capable of being disengaged from the resilient means by the application of a comparatively small force and in a manner that the resilient means can return the pilot valve to said one position with a snap action.

Another object is to provide a controller employing a pilot valve which is opened and closed with a snap action eliminating a constant bleeding of the control gas to the atmosphere and minimizing the amount of gas lost to the atmosphere upon each change.

Another object is to provide a controller for supplying an impulse signal throughout a predetermined time interval which impulse may be terminated during the time interval in response to a rise or fall of pressure in a control fluid.

Another object is to provide a controller of the type employing a pilot valve with a means for over-riding the controller by remote control through the medium of a small pneumatic motor responding to a pressure signal initiated remotely from the controller.

Another object is to provide a clock controlled mechanism having a timing wheel, driven by the clock at a selected speed between one revolution per hour and one

2

revolution per month, wherein the timing wheel has two peripheral grooves each formed with at least 180 regularly spaced slots for the retention of pins therein and arranged to cooperate with the formation of the rim of the timing wheel so as to be self-retaining but easily removable by hand, and a weight bar or equivalent spring-pressed arm hinged at one end, fitted with an inclined plane or cam projecting down into the first of the peripheral grooves and shaped like a saw-tooth so that a pin

- 5 placed in a slot across the groove will, as the wheel rotates, slowly lift the weight bar or spring arm as the pin passes along the inclined face of the cam and then allow the bar to drop by gravity or the spring force as the pin passes the end of the cam. The weight bar has pivoted 10 to it a ratchet toothed lever which, while rising with the weight bar, engages, without moving, the spring means holding the pilot in closed position but capable upon falling of the weight bar or spring-pressed arm of overcoming the spring force holding the pilot in one position whereby 15 the pilot may change its position automatically. The ratchet toothed lever has a crank means secured to it with a saw-toothed profile cam that projects into the second peripheral groove in the timing wheel so that a pin placed in the slot across this groove will, as the wheel rotates, engage and lift this crank to rotate the ratchet toothed lever to disengage the valve closing spring means. The ratchet toothed lever provides a catch which may be disengaged from the spring means by other means as, for example, (1) by means sensitive to a rise in pressure, (2) 20 by means sensitive to a fall in pressure, and (3) by a mechanical trip either acting directly or through the medium of a pneumatic motor responsive to remotely initiated signals.

Another object is to provide a controller for generating timed impulses of a selected time duration with means for interrupting any of the generated impulses during its usual time period and terminating the impulse in response to occurrence of a control condition.

Another object is to provide a time controller for automatically delivering a pressure impulse at selected time intervals for a selected time duration in which any impulse may be terminated short of its pre-selected time duration upon occurrence of a pre-selected condition.

Another object is to provide a controller for delivering pressure impulses of a predetermined duration at predetermined time intervals with means for interrupting either a particular impulse or successive impulses upon occurrence and during the existence of a predetermined pressure condition in which the impulses will continue to be given after cessation of the occurrence of such predetermined condition at their regular time intervals as though there had been no previous interruption in the timing cycle.

Another object is to provide a controller and system 55 utilizing a pilot valve for providing an opening force, which pilot valve is controlled by a resilient means and a means for rendering the resilient means ineffective, wherein the latter means may be responsive to several conditions as well as time dependent upon which condition

60 occurs first and independently of the others, for example, a cycle initiated by a clock timing wheel can be ended by the arrival of a free piston at the tubing head of a well, failing which, it can be ended by a fall in the gas pressure in the casing of the same well, failing which, it can be ended by the clock timing wheel on the expiration of a predetermined time; whichever condition or effect occurs first terminating the cycle.

Another object of the invention is to provide a time controlled controller for both starting and terminating an operation which employs a safety factor in that upon 70 stoppage of the clock in the middle of such an operation which would leave a valve open indefinitely, the oper-

ation is terminated at substantially the same time that it would be terminated by the clock had the clock not stopped in response to occurrence of some condition such as pressure change or arrival of a mechanical part at a predetermined station.

Other and further objects of the invention will appear from a consideration of the specification and the drawings.

In the drawings which form a part of the instant specification and are to be read in conjunction therewith and wherein:

Fig. 1 illustrates the application of this invention to a typical intermitting gas lift installation;

Fig. 2 illustrates this invention as applied to a well having natural flow and equipped with a free piston;

Fig. 3 illustrates on a somewhat enlarged view a trigger mechanism of a remote control for the controller of Fig. 2;

Fig. 4 is an elevational view partially in cross-section illustrating one preferred embodiment of the controller of this invention which is responsive strictly to a time control;

Fig. 5 is an elevational view with parts shown in section of the controller illustrated in Fig. 4 and rotated 90° from the view of Fig. 4;

Fig. 6 is a view taken in elevation with parts shown in section of a modified controller similar to that shown in Figs. 4 and 5 showing the controller equipped for tripping not only on time but also in response to pressure and a mechanical action;

Fig. 7 is a top plan view of the controller shown in Fig. 6; and

Fig. 8 is an elevational view taken at 90° from the view in Fig. 6 and illustrates in section part of the control mechanism.

Referring now to Figs. 4 and 5, a clock 42 rotates a control wheel 43 at a speed suited to the installation to be controlled. The wheel 43 has two peripheral grooves 43a and 43b, a large number of slots 43c, typically 180 or 240, conveniently divisible by 30 (days) or by 12 (hours), and shaped spring pins 44 capable of being placed in any groove and self-retaining by virtue of a light grip in the circumferential recess 45, are utilized.

An upright standard or back plate 46 carries a weight bar bracket 47 whose extension pin 48 is a pivot on which a weight bar 49 can swing in a vertical plane over the rim of wheel 43. A stop 53 limits downward swinging of the weight bar relative to the wheel. The cam 50, movable in a slot 51 in the weight bar and having all slack taken up by a blade spring 52, projects down into the wheel groove 43a and intercepts the path of any pin 44 placed in any slot 43c when the weight bar is at rest on stop 53. Rotation of the wheel 43 and pins 44 then lifts the weight bar slowly and drops it instantaneously when the pin has passed the full length of cam 50. The position of cam 50 is varied by the fine thread screw 54, typically having forty threads per inch, which is rotated by serrated disc 55. The serrated disc is held against accidental movement under influences such as vibration, by the V-shaped extension 56 of the flat blade spring 52 engaging serrations on the rim of disc 55. The disc 55 is clearly marked by divisions, typically twenty-five, so that a change of one division would change the position of cam 50 by one thousandth of an inch.

The weight bar is fitted with a latch assembly in which the transverse spindle 57 is attached to a ratchet lever 58, having a ratchet tooth 58a and at the other end to a time release lever 59 which has a cam 59a similar to the cam 50. The arrangement is such that rocking of lever 59 due to cam 59a engaging a pin 44 will cause the lever 58 to rock to release catch 58a. Cam 59a projects down into the groove 43b of wheel 43 and intercepts the path of pin 44 as the wheel 43 rotates.

Pilot valve body 61 has an inlet valve port 30 to which gas is fed by pipe 28 through a pressure regulator

29 and gas is obtained from such a suitable source. A double-ended two-way pilot valve 31 is normally urged upwards by blade spring 62 which constitutes a resilient means. The blade spring is fixed to bracket 47 and adjusted in strength by rotating the bar 47 and locking same by screw 63. Thus the spring 62 presses valve 31 against seat 30 closing off the supply of gas and simultaneously opening the exhaust port 32.

Attached underneath the clock base 64 is the central column 35 of the fixed distributor disc 37 which constitutes a stator. The stator has a raised circular valving face 65 and a number, typically from twenty to forty according to the number of valves or other devices to be controlled, of holes 66 axially drilled and evenly spaced on a common radius. Thus the holes are arranged circumferentially of the stator. To the holes 66 will be connected small pipes, typically one-quarter inch standard copper tubing leading to valve or other device to be controlled.

The rotating disc distributor or rotor 36 is mounted for turning about the fixed central column 35 and is held in close contact with fixed disc or stator 37 by a spring 67. The rotating friction is relieved by thrust ball bearing 68 and protected from dust by sleeve 69.

Pressure gas from pilot valve 31 is conducted by pipes 33 and 34 to hole 70 in the column 35. A radially drilled hole 71 connects hole 70 with a circumferential groove 72. Groove 72 is isolated within close fitting bore 73 of rotating disc 36 by two seals 74 above and below the groove 72 respectively. On the same plane as radial hole 71 is a radially extending hole 75 passing through one radius of the rotating disc 36 and extending from bore 73 to the outer periphery where it is closed by plug 76. At the same radius as hole 66 in the fixed disc, one port 77 is axially drilled in the rotating disc 36 from the hole 75 to the surface in contact with the raised valving face 65 of the fixed disc 37 and an annularly recessed seal ring 78 provides a pressure seal so that pressure gas from the pilot valve can be delivered by pipes 33 and 34, holes 70, 71, 75 and 77, to any port 66, with which port 77 is brought into alignment or register with which port 77 is brought into alignment or register with substantially without leakage. A soft seal 79 typically of felt soaked in oil and retained in opposing grooves in the discs, excludes dust from the valving face 65.

A means is provided for venting each of the fittings 66 which are not in communication with port 77. This may be accomplished by providing a series of holes 80 drilled in rotating disc 36 in axial alignment, one each with all of the ports 66 except the one which is in register with port 77. This insures that all of the devices to be controlled are vented to atmosphere except the one being supplied with pressure gas through port 77.

Base 64 is secured to the central upright part 35 by set screws 64a and holds the ball bearing assembly 68 against upward vertical displacement. This base plate 55 may support a housing 64b. Attached to the base 64 is a motor cylinder 39 in which a piston 38 is forced against a spring 81 by gas pressure fed to the cylinder by pipe 33. The piston 38 has an extension 82 guided by bushing 83, slotted at 84, and prevented from turning, while free to slide, by a key, typically the nose of screw 85. A ratchet lever 40, pivoted at 86 in the slot 84 of the piston 38, is arranged to act uni-directionally on a series of pins 87 equal in number to ports 66. The pins are fixed to the rotating disc on a common radius to suit the ratchet lever 40 and equally spaced.

In cylinder 39 the bushing 83 is fixed by retaining ring 88 and has an extension 89 which accommodates the return spring 81 and provides a precise stopping point for the outward travel of ratchet lever 40 so oriented with relation to the port 66 and the pins 87 that the port 77 is brought into exact alignment with one port 66 and vents 80 into alignment with all the other ports 66 when piston 38 reaches the end of its stroke abutting the stop 89. At the other limit of piston 38's stroke, the ratchet

lever 40 will be retracted by spring 81 more than the distance between two pins by a marginal working clearance.

It is believed that the operation of this controller is apparent from the foregoing description. The pilot valve housing 61 is provided with the inlet port 30, outlet port 32 and an intermediate port connecting with pipe 33. Pilot valve 31 has two operable positions, the first closing off the inlet 30 while connecting the outlet 32 and pipe 33 so as to vent the latter. The second position of valve member 31 closes port 32 while connecting the inlet 30 with pipe 33. The pilot valve when in its raised position prevents the communication of any signal impulses or gas pressure impulses, but when allowed to fall to its lower or second position, the signal impulses are given. The pilot valve member 31 is biased toward the position for closing outlet 32 as by gravity assisted by gas pressure but a resilient means in the form of the leaf spring 62 normally overcomes the bias to hold the valve member in position to close inlet port 30.

Timed impulses are given by overcoming the spring 62 at timed intervals, whereby the valve member 31 can assume its lower position under the bias, and the impulse duration lasts until the spring 62 is released whereby it may return valve member 31 to its raised position.

The means for rendering ineffective the resilient means 62 includes the clock driven wheel, the weighted arm with its cam connection with the wheel, and the ratchet lever 58. A means is provided for rendering this means ineffective also in response to a clock driven wheel which may be the same wheel. This latter means includes the release lever 59 with its cam 59a engageable by the pins 44 for raising the release lever to thus rock ratchet lever 58 from position where it engages the leaf spring. This terminates the signal impulse upon a timed interval basis.

It will be appreciated that the clock mechanism need not be strong enough to directly provide a force for overcoming the resilient means 62 because the cam 50 has an inclined face 50a which is in engagement with the pin 44 over a prolonged period, thus providing a mechanical advantage capable of raising the arm 49 slowly to the position that lever 58 hooks over spring 62. However, when the pin 44 passes over the lefthand edge of cam face 50a, as shown in Fig. 5, the arm 49 is free to move quickly under the stored energy to quickly render ineffective the resilient means 62. Likewise, the release of the ratchet lever 58 from resilient means 62 is instantaneous to provide a snap action for returning the valve member 31 to its other position.

It is thus seen that the signal impulse is initiated and terminated in accordance with a time cycle. The impulse when once generated is transmitted through the pipes 33 and 34, passages 70, 71 and 75, port 77 and connection 66 to the particular motor valve or other controlled device that is connected to the particular port 66 at the particular time.

The one of ports 66 which is in register with the port 77 is also determined in response to the signal impulse for it is transmitted through pipe 33 to the cylinder 39 to move the piston 38 to the right and thus advance stepwise the rotor to bring port 77 into register with a succeeding one of ports 66.

The controller shown in Figs. 6, 7 and 8 is designed for use in either of the arrangements of Figs. 1 and 2. It is very similar to the controller shown in Figs. 4 and 5, utilizing many of the identical parts, and the basic difference is that it is shown for controlling directly a motor valve and is equipped with means other than time controlled means for limiting the duration of the signal impulse. It is to be understood that while the distributor indicated in the previously described controller is not shown in Figs. 6 and 7, that the apparatus of Figs. 6 and 7 can be employed with such distributor or with a plurality of such distributors in the same manner as the other controller. This illustrates the versatility of the

device and the means for terminating the duration of the signal impulse in accordance with conditions other than time in order to provide a safety factor as well as a factor insuring conservation of control gas and also to provide for remote control of the device.

A base plate 64 with facility 90 for mounting on a pedestal as in the case of the units of Figs. 4 and 5, can also be assembled on the top extension 91 of a conventional diaphragm motor valve such as that shown in Figs. 1 and 2.

All parts similar to those in Figs. 4 and 5 are similarly numbered.

In the case of the conventional motor valve shown in Fig. 2, gas pressure supplied to pipe 33 passes down through a hole in boss 91 to the diaphragm 92 and thus the motor valve is opened by pressure and closed by return spring 93.

In the Figs. 6 and 7 assembly, the horizontal extensions 58c and 58b of the ratchet lever 58 are brought 20 into use for alternative means of releasing the ratchet head 58a from engagement with the spring 62.

As described in respect of Fig. 4, a pin 44 across groove 43a will lift the weight bar 49 by cam 50, ratchet head 58a will be lifted up above the edge of spring 62 25 and spring 60 will cause its engagement therewith and prevent accidental disengagement due to vibration. In the meantime spring 62 is holding valve 31 closed up against seat 30 so that pipe 33 and the diaphragm chamber of motor valve of Fig. 2 are exhausted to atmosphere 30 through port 32. When pin 44 passes by the end of the inclined plane of cam 50 and the weight bar 49 drops against the stop 53, the ratchet head 58a pulls down the spring blade 62 clear of the end of the spindle of valve 31, allowing the latter to close port 32, open port 35 30, transfer pressure to pipe 33 and the diaphragm 92, opening the motor valve.

From this position any force that can disengage the ratchet head 58a from spring 62 will be sufficient to cause the reclosure of the motor valve because, while the weight bar is heavy enough to pull down the blade spring 62, the latter, when freed will give an instantaneous thrust upward on valve 31 and be strong enough to close port 30 against the pressure supplied to it, typically 25 p.s.i., with a snap action.

45 Thus, it will be seen, pilot valve 31 is instantaneously opened and instantaneously closed.

Method No. 1 of releasing the ratchet is by the clock on a time basis. Thus, assuming a timing wheel speed of one revolution per day, a pin 44 is placed across the groove 43b at a point which will come to the top later than the pin across the groove 43a which initiated the opening of the motor valve, then after a lapse of time, cam 59a would be lifted, rotating spindle 57 and releasing the ratchet head 58a. This time delay between the opening and closing of the motor valve, assuming 180 slots 43c, can be varied in steps of eight minutes by moving the pin 44 from slot to slot. It can also be varied in very small steps by micrometer adjustment of the relative position of cam 50 which has a travel relative to the weight bar for more than the distance between two adjacent wheel slots. As previously mentioned, an adjustment of one division of the serrated disk 55 moves the cam $\frac{1}{1000}$ " which varies the time by four seconds. This is satisfactorily small for oil field usage.

60 Thus by time setting, the motor valve can be closed any time from less than one minute to more than 23 $\frac{3}{4}$ hours after the opening, variable by four second steps.

70 This is, of course, the same for the controller of Figs. 4 and 5.

Method No. 2 of effecting a ratchet release is by the arrival at the surface in a well tube of a free piston which commenced its journey from the bottom of that 75 well with a load of fluid above it when the motor valve

of Fig. 2, mounted on the fluid flow line 94 from the tubing head of the well, was opened.

In Fig. 2 a conventional motor valve, opened by pressure on diaphragm 92 and closed by spring 93 is mounted on the flow line 94 from the tubing head flow T 95 of a well.

The Fig. 2 assembly illustrates method No. 2. The gas pressure fed through pipe 28 to the controller is connected also by pipe 96 to port 97 to a unitized flow-T-pilot-valve assembly. In the flow T a cam 98, pivoted on a center 99, is normally maintained by a spring 100 in a position such that the curved part of its profile projects through a slot in pipe 101 to intercept the path of a free piston as it comes up the well tubing. The cam lug 102 abuts one arm 103 of a crank lever 104 whose other arm 105 is forked to engage the head 106 of pilot valve 107. Pilot valve 107 is urged by light spring 108 to close atmospheric exhaust port 109 and open gas pressure supply port 97 but is normally held in its opposite alternate position by the superior force of spring 100 acting through lug 102, and lever 104 on the head 106 of the valve stem. The valve stem has a packing gland 110. The pressure chamber 111 is connected by pipe 112 with a cylinder 113 containing a piston 114 whose rod 115 is arranged to push the ratchet head 58a off the spring 62 allowing it to close the controller pilot 31. This is more fully described in connection with Figs. 6 and 7.

Referring to Figs. 6 and 7 the cylinder 113, attached to the back plate 46, has a slotted extension in which is pivoted a lever 116 acted upon in one direction by the thrust of piston rod 115 and in the other by return spring 117. The lever head 118 is arranged to lie just under the arm 58b of the ratchet lever 58 when its head 58a is engaged with blade spring 62.

When a free piston comes up to the well head behind a fluid column which is flowing through pipe 94 and the open motor valve, it pivots cam 98 outwards against spring 100 and lifts the lug 102 away from the crank lever 104. Spring 108 then moves pilot valve 107 to close the vent port 109 and open the gas supply port 97 whereupon gas is fed to chamber 108, pipe 112, and cylinder 113 to thrust out piston 114 whose piston rod 115 pivots lever 116 whose head 118 lifts the arm 58b releasing ratchet head 58a, closing port 30, venting the gas from the diaphragm 92 through atmospheric exhaust 32 and closing the motor valve.

119 is a manually controlled means of catching and holding a free piston when it is to be retrieved, and 120 is a spring buffer to cushion a free piston arrival at high velocity.

Methods Nos. 3 and 4 of tripping the ratchet and effecting the reclosure of the motor valve are by the use of pressure sensitive means.

Referring to Fig. 1 the pressure which is to control the duration of the signal impulse is shown as the casing pressure of the well. Line 121 connects through line 94a to the casing head and leads to a cylinder 124 in which is a reciprocating piston 123. The details are shown in Figs. 6 and 7. A housing 124 is attached to the controller base 64 by the cylinder 122 to which it is screwed and has an adjustable cap 125 capable of varying the thrust of a spring 126 which is assembled between the under side of the cap 125 and the shoulder 127 of a stem 128 which is in contact at its lower end with piston 123. Stem 128 extends upwards through the cap 125 and carries adjustable nuts 129 arranged one above and one below the head 130 of a trip arm 132 which pivots on a pin 131 and extends through slots in the back plate 46 to engage either the left arm 58c or the right arm 58b of the ratchet lever 58 according to whether trip arm 132 is assembled on the right of the bracket 61a or switched over to the opposite end of swivel pin 131 and assembled on the left side.

When trip lever 132 is assembled on the right of the

bracket 61a, the end of it comes under the arm 58b so that a falling pressure acting on piston 123, allowing an expansion of spring 126 and a descent of the stem 128; pivots trip lever 132 to lift arm 58b effecting the release of ratchet head 58a and, as before, the closure of the motor valve. This constitutes method No. 3.

When trip lever 132 is assembled on the left of the bracket 61a, the end of it comes over the arm 58c so that a rising pressure acting on piston 123, compressing spring 126 and raising stem 128, pivots it in the opposite direction pushing down the arm 58c and similarly closing the motor valve. This constitutes method No. 4. Thus, the release of ratchet head 58a may be in response to either a high or low pressure.

Although the pressure sensitive element is here described as a piston in a cylinder, the use of a flexible diaphragm, a flexible metallic bellows assembly, or other equally well known pressure sensitive elements is contemplated without departure from the spirit of the invention.

Although described in the foregoing and illustrated using a weight bar, it will be understood that spring force can be substituted for the weight to any extent without departing from the spirit of the invention. For example, if the bar where half the weight illustrated and urged downwards by spring means, the functioning would not be altered; similarly, if the spring force were equal to the whole weight, the latter would be unnecessary.

From the foregoing it will be seen that this invention is one well adapted to attain all of the ends and objects hereinabove set forth, together with other advantages which are obvious and which are inherent to the structure.

It will be understood that certain features and subcombinations are of utility and may be employed without reference to other features and subcombinations. This is contemplated by and is within the scope of the claims.

As many possible embodiments may be made of the invention without departing from the scope thereof, it is to be understood that all matter herein set forth or shown in the accompanying drawings is to be interpreted as illustrative and not in a limiting sense.

The invention having been described, what is claimed is:

1. A time controller for supplying a pneumatic impulse comprising a three-way valve with its inlet adapted for connection to a source of gas under pressure and having a first and second outlet, a valve member in said valve movable between two positions, the valve member when in the first of said two positions closing the inlet of the valve and flowingly connecting said two outlets and when in the second of said two positions closing the first of said two outlets and flowingly connecting the inlet to the second of said two outlets, said valve member biased toward said second positions, a resilient means normally urging the valve member toward its first position to overcome said bias, a clock driven wheel, a weight bar pivoted so that a part thereof swings upwardly and downwardly toward the resilient means, a catch pivoted to said weight bar part and having a portion engageable with a part connected to the resilient means upon upward pivoting of the weight bar and to remain in engagement with the resilient means during subsequent downward pivoting of the weight bar, cam means carried by the weight bar and engageable with preselected portions of the clock driven wheel to slowly raise the bar to engage the catch with the resilient means and to thereafter release the bar to pivot downwardly to render the resilient means ineffective to bias the valve member to its first position, means responsive to movement of the clock driven wheel to disengage the catch from the resilient means after lapse of a predetermined time interval after the weight bar has pivoted downwardly whereby the resilient means returns the valve member to its first position, and means for disengaging the catch from the re-

silient means responsive to a control condition and independently of said clock driven wheel and operable to prevent engagement of the catch with the resilient means during the existence of a predetermined control condition.

2. The controller of claim 1 wherein the last mentioned means is pressure actuated in response to predetermined pressure in a pressure system.

3. The controller of claim 1 wherein the last mentioned means is pressure actuated in response to position of a mechanical element.

4. A time controller comprising valve means having a valve element with two positions to alternately supply a gas under pressure to a device and to vent said device, said valve element being biased toward one position, said valve means including resilient means urging the valve element toward its other position, a timing wheel, a weight bar pivoted for upward and downward movement with respect to the valve means, a catch pivoted to the weight bar and engageable upon upward movement of the bar with the valve means to render the resilient means thereof ineffective to hold the valve element in its other position, said catch having a part engageable with a pre-selected part of the timing wheel to disengage the catch from the valve means after the weight bar has moved downwardly and a cam carried by the weight bar and engageable with a part of the timing wheel to move the bar upwardly to engage the catch with the valve means at preselected intervals.

5. The controller of claim 4 in combination with means for moving the cam means along the bar whereby the time interval between engagement and disengagement of the catch with the valve means can be adjusted without alteration of the timing wheel.

6. A time controller for supplying a pneumatic impulse comprising a three-way valve with its inlet adapted for connection to a source of gas under pressure and having a first and second outlet, a valve member in said valve movable between two positions, the valve member when in the first of said two positions closing the inlet of the valve and flowingly connecting said two outlets and when in the second of said two positions closing the first of said two outlets and flowingly connecting the inlet to the second of said two outlets, said valve member biased toward said second position, a resilient means normally

urging the valve member toward its first position to overcome said bias, a clock driven wheel, a weight bar pivoted so that a part thereof swings upwardly and downwardly toward the resilient means, a catch pivoted to said weight bar part and having a portion engageable with a part connected to the resilient means upon upward pivoting of the weight bar and to remain in engagement with the resilient means during subsequent downward pivoting of the weight bar, cam means carried by the weight bar and engageable with preselected portions of the clock driven wheel to slowly raise the bar to engage the catch with the resilient means and to thereafter release the bar to pivot downwardly to render the resilient means ineffective to bias the valve member to its first position and means responsive to movement of the clock driven wheel to disengage the catch from the resilient means after lapse of a predetermined time interval after the weight bar has pivoted downwardly whereby the resilient means returns the valve member to its first position.
